UNITED STATES PATENT OFFICE

LESTER L. JONES, OF ORADELL, NEW JERSEY

AMPLIFIER

Application filed October 5, 1929. Serial No. 397,633.

This invention relates to amplifiers, and more particularly to vacuum tube amplifiers of the untuned or automatically tuned type.

In my Patent No. 1,673,287 issued June 12, 1928, I have explained how an audion or electron emission tube amplifier stage having fixed circuit constants may be arranged to automatically tune to the frequency of energy supplied thereto within a desired working frequency range. In my copending application, Ser. No. 205,934, filed July 15, 1927, since issued on July 15, 1930, as Patent No. 1,770,525, of which the present application is a continuation in part, I have illustrated the application of this principle of automatic tuning to a receiver consisting of a tuned selector followed by an untuned cascade amplifier. The first tube of such an amplifier is arranged to act as a substantially reactionless link stage so as to prevent reaction from the amplifier upon the selector, while the second tube of the amplifier is arranged both as an additional transition stage between the reactionless stage and a group of automatically tuned amplifier stages, to correct for residual reaction permitted by the first transition stage, and as an automatically tuned stage. The remaining stages are designed for automatic tuning, and the primary object of my present invention centers about the provision of an improved electron discharge tube cascade amplifying system of the so-called untuned type, or more accurately, having fixed circuit constants.

In my aforesaid Patent No. 1,673,287, I have disclosed how an electron emission tube may be arranged to be automatically tuned over a range of frequencies. For this purpose it is there assumed that the output circuit of the tube works into a suitable succeeding circuit, which preferably has the electrical characteristics of a small fixed loss-free capacitance. The output circuit of the tube is made naturally resonant to a frequency lower than the lowest frequency of the working frequency range. Frequencies in the working frequency range are therefore higher, making the output circuit effectively capacitive, and therefore characterized by decreasing impedance with increasing fre-

quency, which in turn causes decreasing radio frequency potential variation on the anode of the tube, and therefore a decrease in the apparent input capacitance of the tube with increasing frequency, which may be utilized for automatic tuning by a proper selection of the input circuit connected to the tube.

If it is desired to have a plurality of automatically tuned stages arranged in cascade, instead of merely a single stage, an immediate difficulty arises because of the fact that the output circuit of any tube preceding the last tube, instead of consisting of a high inductance which remains resonant to a constant frequency lower than the working frequency range, operates as an automatically tuned circuit and therefore tends to remain in resonance with the working frequency.

A primary object of my present invention is to overcome the foregoing difficulty, and to make possible the use of a plurality of automatically tuned stages coupled directly in cascade. To this end I divide the working frequency range into a plurality of portions, and I arrange the automatically tuned stages to each tune over a different one of the frequency portions. I then couple the stages directly together in the order of decreasing frequencies, whereby each coupling circuit, while capable of being automatically tuned to any frequency in its portion of the frequency range, is nevertheless resonant to a frequency lower than the portion of the frequency range to which the preceding coupling circuit is capable of being automatically tuned. In this manner automatic tuning of a plurality of stages coupled directly in cascade is obtainable, and at the same time no disadvantage is incurred in operating each stage over only a portion of the working frequency range, for the reason that with present commercial tubes, and without exceptional precautions, it is anyway difficult to obtain automatic tuning over all of so broad a range as the commercial broadcast range.

Volume control is desirable to vary the gain in an amplifier, and is obtained by varying the steady or operating anode potential or the control electrode bias potential of the am-

plifier tubes. A change in either of these operating potentials changes the amount of anode current and potential variation resulting from a given input potential variation, and therefore changes the apparent capacitance of the input circuit of the tube. Also, a change in the operating potential applied to either the anode or the control electrode changes the anode to cathode tube impedance and therefore changes the load across its output transformer or other circuit. These two changes affect the tuning of the circuits and the stability thereof. For example, if the anode potential is materially reduced the alternating anode potential for a given alternating grid potential is reduced, and the apparent input capacitance of the tube is therefore greatly diminished. This raises the frequency of the circuit, so that it may become inductive and therefore regenerative for some frequencies. At the same time the anode to cathode impedance of the tube is greatly increased, thereby effectively removing a resistance load across the output transformer. This condition gives rise to an oscillatory or unstable state of the amplifier at some portion of the range of volume control.

The present invention, as a continuation of my copending application aforesaid, deals with these secondary problems which arise when it is attempted to apply volume control to an automatically tuned amplifier, and a desideratum of the present invention centers about the application of volume control means to such an amplifier, and to improvements in the amplifier which obviate instability when volume control is applied thereto.

In the automatically tuned stages the output circuits are naturally resonant to frequencies lower than the input circuits, and the stages normally are therefore stable. This relation may be lessened and even reversed at some point over a wide range of volume control, and accordingly one object of the present invention is to so adjust the input and output circuits of these stages, within the range of dimension giving the desired automatic tuning, that the natural resonance frequency of the input circuit remains higher than the natural resonance frequency of the output circuit over the full range of volume control.

In one of the amplifier stages, coming between automatically tuned stages, the input transformer is necessarily of greater inductance than the output transformer, and the latter is therefore naturally resonant to higher frequencies than the former, and therefore is inductive and regenerative in the working frequency range. However, their wide difference in frequency lends stability which tends to prevent oscillation in spite of the regenerative reaction in this stage, but variations in the constants of the circuits

in the range of volume control may lessen this frequency difference and again lead to instability. Accordingly, a further object of my invention is to overcome this possible source of instability, which I do by making the input and output circuits more widely different in frequency than would otherwise be necessary, and sufficiently so to prevent instability over the range of volume control.

Variation in the steady or operating potentials applied to the tubes I have found is disadvantageous when applied to the first or transition tubes of the amplifier. For example, if the first tube is subjected to a variable operating potential the apparent input capacitance into which the selector works is made variable, and this will throw the last tuned circuit of the selector out of tune relative to the preceding tuned circuits, and therefore lessen the selectivity thereof. If volume control is applied to the second transition tube a reduction in potential will reduce the apparent input capacitance of the second tube and therefore change the capacitive load on the output circuit of the first tube, which in turn varies the reaction of the first tube, making it regenerative.

A further object of my present invention is to overcome the foregoing difficulties, and to this end I find that I am able to prevent changes in the selectivity or/and tuning of a selector over the entire range of volume control by obtaining the desired volume control through variation of the operating potential applied to the last or automatically tuned group of amplifier tubes, but not to the transition stages.

To the accomplishment of the foregoing and such other objects as will hereinafter appear, my invention consists in the methods and the circuit elements and their relation one to the other as hereinafter are more particularly described in the specification and sought to be defined in the claims. The specification is accompanied by drawings in which:

Fig. 1 is a wiring diagram for a circuit embodying some of the features of my invention;

Fig. 2 is a wiring diagram of a receiver embodying further and improved features of my present invention;

Fig. 3 is a schematic drawing explanatory of one of the features of my invention;

Fig. 4 is a dimensioned section through an insulation spool suitable for astatic inductances employed in the amplifier;

Fig. 5 is a dimensioned section through an insulation spool suitable for some of the bifilar astatic transformers employed in the amplifier;

Fig. 6 is a dimensioned section through a spool for a bifilar transformer employed in the amplifier;

Fig. 7 is a dimensioned section through a

spool for a multi-section bifilar astatic transformer employed in the amplifier; and

Fig. 8 is a wiring diagram for a slightly modified amplifier similar to that shown in Fig. 2.

Referring now to Fig. 1 of the drawings, I show a radio receiving apparatus comprising a selective system generally designated by the bracket S and an audion amplifying system generally designated by the bracket A, the selector system S comprising a plurality of circuits in cascade having variable constants to effect selectivity, and the amplifier A comprising cascaded electron discharge tube stages having fixed circuit constants, and being coupled to the last selective circuit of the selector S.

The selector system S is described in greater detail and claimed in my copending application, Ser. No. 205,935, filed July 15, 1927, while the inter-relation of the selector and the amplifier and the mode of preventing reaction by the latter upon the former is more particularly described and claimed in my copending application, Ser. No. 205,934, also filed July 15, 1927, since issued as Patent No. 1,770,525, of which the present application is a continuation in part, the present application being directed to the amplifier, as there disclosed, and also to further improvements therein, here disclosed in connection with Figs. 2 through 8 of the drawing.

The selector system comprises three selective circuits S^1 , S^2 and S^3 , preferably inductively coupled together. The first selector circuit S^1 is coupled to an energy receptor *ant* by means of a condenser 10, and the last selector circuit S^3 is coupled to the input circuit of the first tube of the amplifier A.

In order to make this selective system S functionable in a radio receiving apparatus where amplification is subsequently accomplished the selector system must be associated with an amplifier of proper characteristics, the amplifier being designed to prevent reactions upon the selector system which tend to destroy the selectivity thereof. Also, the amplifier should possess inherent stability, and the amplifier as a whole should be prevented from picking up any energy except that fed thereto from the selector system, and yet the amplifier must be sufficiently powerful to increase the signal to a volume suitable for operating the audio system even though the couplings in the selector system be made quite loose to realize full geometric selectivity.

The amplifier A comprises five tubes, T^1 , T^2 , T^3 , T^4 , and T^5 . Each of the tubes comprises the usual grid, plate and filament, *g*, *p* and *f* respectively, the filaments of the tubes being connected by means of filament circuits to the A battery designated $-A+$. The filament circuits may be suitably provided with

fixed resistors such as *r*. The B battery designated $-B+$ is connected in the usual way to the A battery and to the output circuits of each of the tubes, a bypass condenser 21 being employed connecting the plus side of the B battery to the minus side of the A battery. The input and output circuits of the tubes are connected to the tube electrodes and batteries as shown in the drawings.

The pair of tubes T^1 and T^2 are coupled together and to subsequent circuits of the series in such a way as to eliminate or balance all of the reactions at the input terminals of the tube T^1 throughout the wave length range of the receiver. To balance the reactions at the input terminals of the first input circuit i' , the circuit network of the amplifying tubes T^1 and T^2 are so organized as to balance or neutralize reactions, so as to cause such network to act or behave as a preferably capacitive reactance which is pure, in order to avoid either damping or regeneration. To permit of uni-control for the selective system S, this amplifier circuit network should further be designed so as to produce a constant capacitance at the input terminals of the first input circuit i' .

To attain this balance or neutralization of the reactions at the input terminals of the first tube T^1 , I first fix the constants of the output circuit o' in accordance with the principles described and claimed in my copending application Ser. No. 51,569 of August 21, 1925, now Patent No. 1,713,132 of May 14, 1929, or in my Patent No. 1,620,661 of March 15, 1927, the natural frequency of this output circuit in connected circuit being greater than the highest frequency of the whole frequency range through which the input circuit i' is tunable, so that there are produced feed-back reactions from the output circuit o' to the input circuit i' over the whole frequency range of the receiver. For neutralizing this feed-back reaction, I employ resistance means in the plate circuit of the tube T^1 , which resistance means is selected of such a magnitude as to cause a feed-forward action from the input to the output circuit equal to the feed-back action produced by the output circuit through the capacitive coupling of the tube structure. This resistance is represented as R' in Fig. 1 of the drawings, and is arranged preferably between the tube anode and the inductance of the output circuit.

The output circuit o' with this determined characteristic is then coupled to the input circuit i' by means of a coupling condenser K and an inductance M, the condenser K being tapped at an effective mid-point of the resistance R' as shown in the drawings, the capacity K and inductance M when taken in series having preferably a natural frequency lower than the lowest frequency of the band to be transmitted through the amplifier. Preferably also the plate side of the

resistance R' is shunted by means of an inductance N and a condenser D . The inductance M may be loosely coupled to the plate inductance L' , but preferably is closely coupled thereto.

As an example of suitable magnitudes of these constants the section of resistance R' between the plate and the intermediate tap may be 920 ohms, the remainder of the resistance R' about 707 ohms, the coupling condenser K about 250 mmf.'s, the inductance N 22 microhenrys, and the condenser D 150 mmf.'s. The inductance M is preferably divided into two sections, one section transformer coupled to the inductance L' and the other a free section, the free section being about 485 microhenrys and the transformer coupled section about 150 microhenrys, both arranged so as to inductively aid each other. The transformer coupled parts are preferably bifilar wound.

With this arrangement and with these constants there are residual variations in the exact balance of the feed-forward and the feed-back reactions over the wave length range due largely to feed-back reactions from the tube T^2 (distant stage feed-back as distinguished from adjacent stage feed back), these variations being of the order of magnitude of about 5% of the reaction due to an adjacent stage feed-back. In accordance with my invention these residual variations in the balance of the feed-forward and feed-back reactions are compensated for (so that an exact balance between the feed-back and the feed-forward reactions are obtained) by producing variations in the input capacitance of the second tube T^2 which may be done by predetermining the characteristics of its output circuit o^2 . This may be accomplished, first, by selecting the constants of the output circuit o' so as to just neutralize on the long waves, this producing a residual over-damping for the short waves, and second, by then neutralizing these residual damping reactions by producing a varying input capacitance for the second tube T^2 . This input capacitance should rise or increase at the longer wave lengths or, conversely stated, should decrease at the shorter wave lengths so as to neutralize the increasing damping reactions at such shorter wave lengths. This rising input capacitance with increasing wave lengths I effect by selecting the output circuit o^2 to have a natural frequency of the order of and preferably lower than the lowest frequency of the wave length band. Otherwise stated, this means that the output circuit o' of the tube T^1 is organized so that over the wave length band there is produced an energy feed-back reaction from the output circuit to the input circuit through the grid-plate capacitive coupling of the tube neutralized except for a residual feed-back reaction at the long waves of the wave length

band; and the output circuit o^2 of the tube T^2 is organized so as to be effective for producing a rising input capacitance of the second tube at the longer wave lengths for neutralizing this residual feed-back reaction.

The tube T^2 , is also in this way incidentally arranged to partly provide automatic tuning, in a manner which will be described in further detail in connection with tubes T^4 and T^5 , but in the case of tube T^2 , the input circuit is made capacitive rather than resonant, with a view to obtaining a corrective effect upon tube T^1 so as to make the amplifier A perfectly reactionless upon the selector S . In other words, the tube T^1 provides some gain but is primarily designed as a reactionless link between the amplifier and the selector. The tube T^2 provides substantial gain, and is partly automatically tuned, but its circuit constants are primarily intended to further improve the reactionlessness of tube T^1 .

The amplifier coupling tubes T^1 and T^2 described also possess an amplification characteristic which increases with the wave length. This characteristic is extremely desirable in connection with the cascaded capacitively tuned circuits preceding these tubes, and especially when such circuits are used in connection with the loop type of receiving antenna. It has been found experimentally that in radio receivers of this type there is a considerable loss of sensitivity at the longer wave lengths as compared to that obtained at the shorter wave lengths. This loss of sensitivity is in part due to the lower reception efficiency of the loop at long waves, and in part due to the less favorable ratio of L/C which is obtained at the longer waves with capacitively tuned circuits. Although each tuned circuit shows a relatively small drop in amplification, of the order of 3 to 1, the cascading of these circuits causes a geometric increase in the ratio which again compounds with the drooping characteristic of the loop so that where three tuned circuits are used in cascade with the loop receptor, the relative sensitivities at the extremes of the wave length range are widely variable. The addition to such a capacitively tuned system of a pair of untuned amplifier tubes (T^1 and T^2) having a sharply rising sensitivity with wave length tends to correct for the decrease in sensitivity and produces a receiver which responds much more uniformly to signals at the various wave lengths within the range. I have found that the non-tunable transformer p^2s^2 having the resonant frequency described will tend to produce a sharply rising amplification characteristic desired. The rising amplification characteristic of this untuned transformer is compounded with the rising amplification characteristic due to the circuit KM which couples the output o' and the input i^2 , this coupling apparatus and its function to produce the rising amplification being described

and claimed in my copending application Ser. No. 182,220 of April 9, 1927, now Patent 1,770,524 granted July 5, 1930.

I have further found that in order to secure the input capacitance characteristic desired the second or short wave mode of oscillation of the transformer p^2s^2 must be either entirely eliminated or moved to a frequency range higher than the highest frequency to which the tunable input circuit may be adjusted. In addition to this, it is also desirable that this transformer have the highest possible efficiency over the wave length range. I have discovered that it is possible to secure this combination of conditions by constructing the transformer bifilarly as described and claimed in my aforesaid application Ser. No. 195,631 to transformer and coil system since issued on October 22, 1929, as Patent No. 1,732,937. Briefly considered, this transformer is wound with a pair of wires twisted together with a pitch relatively large compared to the wire diameter. One of these wires forms the primary winding and the other the secondary winding, and similar ends of the two windings connect with the plate voltage supply and filament connections of the tube. The bifilar winding is preferably random wound in a relatively narrow slot so as to form a coil of relatively small distributed capacity and of relatively high inductance. The inductance is made sufficiently great to give a natural frequency to the transformer in connected circuit as aforescribed.

Following the coupling tubes T^1 and T^2 , the amplifier A is made to comprise a plurality of so-called untuned audion amplifiers T^3 , T^4 and T^5 , followed by a detector tube $Det.$, which latter is connected to the audio amplifying system. While I have termed the tubes T^4 and T^5 untuned amplifiers, in accordance with their designation in the prior art, I construct these tube stages in accordance with the principles described and claimed in my aforesaid Patent No. 1,673,287, the said amplifying stages functioning for producing what I prefer to call an automatic tuning effect, causing the production of high and efficient amplification over a considerable or relatively wide wave length range or band.

The tube T^5 works into a detector tube the input circuit of which has the electrical characteristics of a small fixed loss free condenser. Transformer p^5s^5 is made naturally resonant in circuit to a frequency lower than the lowest frequency of the working frequency range so that frequencies in the working frequency range are higher, and the transformer is effectively capacitive and characterized by decreasing impedance with increasing frequency which, in turn, causes a decrease in the apparent input capacitance of the tube with increasing frequency. The

transformer p^4s^4 is selected to resonate with the input capacitance of tube T^5 over the lower frequency portion of the working frequency range. For the higher frequency portion of the working frequency range the transformer p^4s^4 is a relatively large inductance, and is resonant to a frequency lower than the higher frequency portion. The input circuit of tube T^5 is effectively the output circuit of tube T^4 because of the substantially unity coupling in a bifilar transformer. The said resonance frequency of this input circuit therefore in turn causes a decreasing apparent input capacitance with increasing frequency in tube T^4 for the higher frequency portion of the complete frequency range. Transformer p^3s^3 is selected to resonate with the apparent input capacitance of tube T^4 over the higher frequency portion of the range. In this manner the complete working frequency range is divided into a plurality of portions, and each of the stages T^4 and T^5 is automatically tuned over a different one of the frequency portions. The stages T^4 and T^5 are coupled directly together but in the order of decreasing frequencies, so that the transformer p^4s^4 , for example, while automatically tuned to a frequency in the lower frequency portion of the range, is not automatically tuned to a frequency in the higher frequency portion of the range, and is suitable for causing automatic tuning of transformer p^3s^3 to said higher frequency portion of the working frequency range.

It is of course possible to carry out the general theory of this arrangement by subdividing the working frequency range into as many portions as may be desired and employing a similar number of automatically tuned stages. However, inasmuch as the complete group of automatically tuned stages consists in effect of only one highly efficient stage and a remainder of untuned and therefore less efficient stages it is obvious that each stage should most preferably be operated over as large a range of automatic tuning as is conveniently and efficiently possible, and to use only so many automatically tuned stages coupled directly in cascade as may prove necessary to cover the desired working frequency range.

This automatic tuning I accomplish, more specifically, by coupling the tube structures T^8 and T^4 with a transformer p^8s^8 having a natural wave length of about 318 meters, then coupling the tube structures T^4 and T^5 by means of a transformer p^4s^4 having a natural wave length of about 343 meters, and coupling the tube structure T^5 with the detecting tube $Det.$ by a transformer p^5s^5 having a natural wave length of about 650 meters. Each of these three transformers is preferably a bifilar transformer of the kind aforescribed in connection with trans-

former p^2s^2 , the first being wound with about 210 turns, the second with 225 turns, and the third with 450 turns. The input circuit of the detector is also preferably provided with a free section of inductance 25, dimensioned in accordance with an invention which is further described and claimed in a copending application of Lester L. Jones and Jacob Yolles, Ser. No. 10 402,378 filed October 25, 1929. These various circuits are connected to the A and B battery as shown. The foregoing transformer constants assume the use of the 201A type of tube, in which the grid to plate capacitance is 15 of the order of 8 mmf., the plate to cathode impedance is of the order of 8000 ohms, and the amplification constant is of the order of 8.

The principle underlying this arrangement 20 of amplifying tubes is that the longer natural wave length of the last transformer of the series (p^5s^5) has the effect of producing a rising input capacitance change with increasing wave length for the last amplifying 25 tube T^5 , which is suited or made to coincide with that desired characteristic of the input circuit of said tube T^5 which would cause the said input circuit to vary its resonance frequency and thus to automatically tune 30 itself over a considerable portion of the total wave length band. This same relation is carried out in the coupling of the tube T^4 to the tube T^3 , the natural wave length of the transformer p^4s^4 being greater than the natural wave length of the transformer p^3s^3 , and causing tube T^4 to be automatically 35 tuned to the lower wave length portion of the total wave length band.

The inter-relations between the circuits in 40 series should also be considered. Thus the output circuit of tube T^4 , being tuned to 343 meters, is tuned to a wave length that this output would have if the next tube T^5 had no relay action. However, when tube T^5 45 has relay action, its tube input capacitance is higher than the geometric capacitance by an amount due to the reaction of the output circuit of tube T^5 . This causes a rise in the natural wave length of the 343 meter transformer, bringing it up to the region of 450 meters. The tube input capacitance curve of tube T^4 is therefore not like the tube input capacitance curve of tube T^5 , because the 50 output circuit of tube T^4 , instead of having a single resonant frequency, has a range of resonant frequencies determined by the automatic tuning effect of tube T^5 on the 343 meter transformer. The output circuit of tube T^5 , which is designated as a 318 meter 55 transformer, is a compromise for the capacitance characteristic of tube T^4 . The output circuit of tube T^5 by the arrangement shown is automatically tuned to be held resonant over a wave length band of 320 to 450 meters, 60 while the output circuit of tube T^4 is auto-

matically tuned to be resonant over a range of 350 to 550 meters. Thus the three transformers are in effect two pairs of transformers, each pair attaining automatic tuning over a given and different wave length band, and both pairs covering the desired range of frequencies with good gain, and nearly the full range of frequencies with automatic tuning.

The specified natural wave lengths of 318, 343, and 650 meters refer to the transformers connected in circuit but without placing the tubes in operation. When tube T^5 is operated its apparent input capacitance is greater than the geometric capacitance, and this increases the wave length of the circuit between tubes T^4 and T^5 . This increase in capacitance, of course, is a variable dependent upon the wave length of the energy being received by the amplifier, and is of such a value that the wave length of transformer p^4s^4 is increased from 343 to around 450 meters when amplifying energy having a wave length of 450 meters. As the wave length of the received energy is increased the wave length of transformer p^4s^4 is increased together therewith, and accurate automatic tuning, by which I mean coincidence of the received and resonant frequencies, may then be obtained. For long wave lengths approaching 650 meters there is a slight departure from coincidence owing to the fact that the transformer p^5s^5 is itself resonant to a wave length of only 650 meters, and not resonant to a frequency lower than the received frequency when the received energy is about 650 meters in wave length.

When the wave length of the received energy is decreased below say 450 meters the input capacitance of tube T^5 falls off only very slightly, so that with a received wave length of say 300 meters the natural wave length of transformer p^4s^4 might be say 425 meters, and with a received wave length of 200 meters the natural wave length of transformer p^4s^4 might fall off to say 400 meters.

Transformer p^3s^3 has a natural wave length connected in circuit and without relay action of about 318 meters. When tube T^4 is given relay action its input capacitance is increased, but at low wave lengths the increase is very slight. For example, with received energy of 200 meter wave length the output transformer p^4s^4 , being resonant at say 400 meters, is far off resonance and constitutes a small output impedance, and therefore causes but little increase in the input capacitance of tube T^4 , bringing the wave length of transformer p^3s^3 up to, say, 325 meters. When amplifying energy having a wave length of 300 meters the input capacitance of tube T^4 is further increased, giving a natural wave length to transformer p^3s^3 of, say, 340 meters. From this point on the re-

ceived and resonant wave lengths of transformer p^3s^3 run in substantial coincidence up to about 425 meters. From that point on the received and natural wave lengths begin 5 to depart from coincidence owing to the fact that the wave length of transformer p^4s^4 , while it begins to increase, only does so enough to remain in resonance with the received frequency, and therefore no longer 10 fulfills the pre-requisite condition for an automatically tuned stage that the output circuit thereof be resonant to a frequency lower than the received frequency.

The resonance curve of an automatically 15 tuned stage is broad or flat topped compared with that of an efficient tuned circuit, and there is a substantial range at either side of exact coincidence of frequencies where very 20 excellent gain is obtained due to automatic tuning in spite of a departure from coincidence, and it is with reference to this broader range of automatic tuning or efficient amplification that the wave length range of transformer p^3s^3 is considered to be from 320 to 25 450 meters, and that of transformer p^4s^4 is considered to begin as short as 350 meters. The specified long wave length for transformer p^4s^4 of 550 meters is far lower than the broad range of automatic tuning, and 30 is even considerably lower than the range of exact coincidence, but 550 meters is specified because the amplifier is assumed not to be required for use with longer wave lengths.

Each stage does not cover exactly half of 35 the range, the practice being to cover slightly more than half of the range with the last stage. The size of the input circuit for the last amplifier tube is determined in order to obtain the maximum amplification from 40 that stage over as much of the frequency band as the input capacitance of the last tube makes available for automatic tuning. This fixes the output transformer and therefore the input capacitance characteristic of the 45 next to the last tube. By measuring and plotting the input capacitance characteristic of the next to the last tube, a value of input inductance for this tube may be selected which utilizes most effectively the variable 50 portion of the thusly plotted curve for automatic tuning. This determines the range of the tube T^4 , while the balance of the band may be carried by the tube T^5 .

Referring now to Fig. 2 of the drawing, 55 there is a selector having variable circuit constants for tuning, followed by an amplifier having fixed circuit constants, the arrangement being in general similar to that set forth in Fig. 1 and in my copending application 60 previously referred to, except that in this case these are four resonant circuits. It may further embody improvements set forth in a copending application of Lester L. Jones and Jacob Yolles, Ser. No. 403,160, filed October 29, 1929.

Energy collected on any suitable antenna circuit 2 is fed to a first resonant circuit 4, which is loosely coupled to a second resonant circuit 6, which in turn is loosely coupled to a third resonant circuit 8 by means of a small auxiliary coil 10, and the resonant circuit 8 is loosely coupled to a fourth and final resonant circuit 12. The various tuning circuits are loosely coupled in order to avoid double resonance peaks, and the circuits are suitably positioned or shielded so that non-adjacent tuning circuits are effectively decoupled. 70

The received energy of selected frequency is supplied to the input circuit of a tube T^1 , the output circuit of which includes a coil 16, 80 which is inductive within the working frequency range and therefore causes a regenerative reaction. Resistance 18 is arranged in series with the inductance 16 in order to cause a feed forward of energy through the tube T^1 which tends to neutralize the regenerative reaction of the inductance 16, and a condenser 20 is preferably connected in parallel with the resistance 18, all in accordance with the disclosure of my copending application, Ser. No. 397,632, filed October 5, 1929. This complex output circuit serves to make the tube T^1 approximately reactionless, so that its input characteristic is nearly that of a pure condenser of low fixed capacitance, this 90 characteristic being most suitable as not affecting the tuning range, the damping, and the selectivity of the resonant circuit 12 of the selector. 95

The capacitance should be pure because the 100 introduction of resistance in the tuned circuit will, if positive, broaden the tuning of the last circuit and necessitate closer coupling of the preceding circuits, thereby broadening the tuning of these circuits also. On the other hand the introduction of negative resistance may make the circuit too selective or even cause oscillation. The capacitance should be fixed in order to make possible unic 105 control of the variable condensers of the selector without necessitating a specially shaped condenser plate for the condenser of the last tuned circuit. The capacitance should be small in order not to reduce the 110 range of tuning obtainable from variable condensers of given magnitude. 115

The output of tube T^1 is fed to tube T^2 through a bifilar transformer 21, the primary of which is connected in parallel with the complex output circuit previously described, and the secondary of which is connected across the control electrode to cathode circuit of the tube. Succeeding amplifier tubes T^3 , T^4 , and T^5 are respectively connected in cascade through bifilar transformers 24, 28, and 32. The amplified output from tube T^5 is supplied to a detector tube 40 through a bifilar transformer 36, in series with the secondary of which there is connected a free grid inductance 38. The radio 125 130

frequency and audio frequency components of the detector tube output are separated by a filter section 42, the audio frequency component being supplied to an audio frequency amplifier or a reproducer through connections to the terminals marked "Output".

Considering the second stage including the tube T^2 more in detail, the transformer 24 is selected to be naturally resonant when in circuit to a frequency lower than the lowest working frequency in order to obtain a rising apparent input capacitance with decreasing frequency for the tube T^2 . In the system of Fig. 2, the output circuit of the tube T^1 is given a substantially higher impedance than would be correct for a reactionless stage, this being for the purpose of substantially boosting the amplification gain therein, as described more particularly in my copending application Ser. No. 397,632, filed October 5, 1929, previously referred to. As set forth in said copending application, I have found that both the inductive and resistance components of the output circuit of the tube T^1 may be each increased to a value approximately double that for producing a reactionless stage, the impedance of this circuit being doubled in effect, and this producing a substantially doubling in the gain for the tube T^1 .

Doubling this impedance causes residual reaction through tube T^1 , and this reaction may be made regenerative over the low frequency end of the range by increasing the feed forward resistance 18 slightly less than proportionally to the increase of the inductance 16. The reaction will still be degenerative at the high frequency end of the range because the slope of the reaction curve differs from that desired. To correct for regenerative reaction capacitance may be hung onto the anode terminal of the output circuit of tube T^1 . The input circuit of tube T^2 is therefore not correctly automatically tuned, but rather is made capacitive, which may be done by selecting a transformer 21 with a larger inductance than would be correct for automatic tuning, because for resonance the capacitance then should be decreased, and not being decreased, is in excess. But the effective capacitance should decrease at the high frequencies and increase at the low frequencies, for more regeneration is needed at the high frequencies and more degeneration at the low frequencies, in order to change the slope of the reaction curve. This is accomplished by the variation in input capacitance of tube T^2 obtained by proper selection of the output circuit of tube T^2 . Incidentally, the gain in stage T^2 is augmented by the approach to automatic tuning which is meanwhile obtained in the input circuit of tube T^2 . The design of the circuits of tubes T^1 and T^2 is set forth in detail in my aforesaid copending application Ser. No. 397,632.

The remainder of the stages may best be described starting at the end of the amplifier and working backward. The detector tube 40 having a low impedance output circuit for radio frequency energy has an apparent input capacitance which is small and fixed. This is most suitable for automatic tuning, and transformer 36 is selected to be naturally resonant in circuit to a frequency lower than the lowest frequency in the working frequency range. For frequencies in the working frequency range the transformer 36, or more properly the output circuit of tube T^5 , is capacitive, and therefore decreases in impedance with increasing frequencies, which decreases the radio frequency potential on the anode of tube T^5 , and consequently causes a decrease in apparent input capacitance with increasing frequencies, as is desired for automatic tuning. For the available range of variation in capacitance the transformer 32 is selected to obtain automatic tuning of tube T^5 over as large a portion of the range as is available beginning at the low frequency end of the range.

Transformer 32 is not suitable for automatic tuning of the input circuit of tube T^4 over the same frequency portion because transformer 32 is kept in resonance to such frequencies. However, this transformer is related to frequencies higher than the portion to which transformer 32 is automatically tuned just as transformer 36 is related to the lower frequency portion, that is to say, transformer 32 is naturally resonant to a frequency lower than the portion of the range of frequencies to which the input circuit of tube T^4 is to be automatically tuned. Therefore, for frequencies lying in the higher frequency portion of the working frequency range, the output circuit of tube T^4 is capacitive and therefore decreases in impedance with increasing frequencies and so causes the decrease in the apparent input capacitance of tube T^4 with increasing frequencies which is desired for automatic tuning. Transformer 28 is of small inductance, selected to resonate with the range of apparent input capacitance of tube T^4 to the higher frequency portion of the working frequency range.

Tube T^3 differs from the other amplifier tubes in having an input circuit of high inductance and an output circuit of low inductance. This tube is therefore not suitable for automatic tuning, but on the other hand, it causes an increase in amplification at the lower frequencies, and this is desirable in an amplifier receiving its energy through a selector which is capacitively tuned, like the selector here illustrated, because such a selector is less efficient at the lower frequencies, and by making the amplifier more efficient at the lower frequencies it is possible to make the selector and amplifier working together as a unit have a uniform response.

It will be noted that in the case of tube T^2 the output circuit is of large inductance, and naturally resonant to a low frequency, which tends to make the output circuit capacitive and degenerative in the working frequency range, so that the stage is inherently stable. Likewise, transformers 28, 32, and 36 have successively increasing inductance, and therefore are naturally resonant to distributed 10 and successively decreasing frequencies, so that the output circuits of tubes T^4 and T^5 are capacitive, thereby making their reaction degenerative, and making the stages inherently stable. In the case of tube T^4 which is automatically tuned over only the higher frequency portion of the frequency range the output circuit including transformer 32 is inductive and therefore regenerative in the lower frequency portion of the frequency 15 range, but this stage is nevertheless inherently stable for the reason that the input circuit of tube T^4 including the transformer 28 can never attain resonance and therefore cannot oscillate in the lower frequency portion of the frequency range. In the upper frequency portion of the frequency range where the input circuit of tube T^4 can oscillate the output circuit is effectively capacitive and degenerative, thus preventing oscillation. Tube T^5 , 20 unlike tubes T^4 and T^6 , has an input circuit of large inductance and an output circuit of small inductance, and therefore is regenerative and tends to instability, but oscillation is avoided by the wide frequency separation between the natural frequencies of transformers 24 and 28, in combination with the substantial load on the output circuit caused by the impedance of the tube T^2 . This load is placed effectively across all oscillatory input 25 circuit elements of tube T^5 by reason of the nearly unity coupling obtained in the bifilar transformer 24.

In accordance with further features of my invention volume control is applied to this 30 amplifier. It is desirable that the volume control means be capable of varying the amount of amplification over wide limits. For example, in a five-stage untuned amplifier the control of volume from a whisper to full loud speaker volume for all stations, both near and far, requires a variation of amplification ranging from full power or an amplification of 10,000 or more down to an amplification of less than one, i. e., an attenuative condition. 35 Some methods of securing this variation of total gain are by varying the anode potential or by varying the bias on the control electrodes of the tubes. In either of these methods there occurs a condition in which, the tube 40 impedance being greatly increased, the resistance load due to the anode to cathode resistance of the tube is reduced and effectively removed from the fixed transformers. At the same time the apparent input capacitance 45 of the tubes at any given wave length is re-

duced by a large amount from the value it has at full amplification, which raises the natural frequency of the adjacent transformer, so that it may become inductive and regenerative in the working frequency range. This 70 combination of unloaded transformers and variations from normal automatic tuning in the direction of regeneration gives rise to an oscillatory or unstable condition in the amplifier. This defect is more sharply felt in 75 the case of volume control obtained by variation of control electrode bias than in the case of variation of anode potential for the reason that the tube impedance changes more rapidly as a function of the amplification gain when 80 the gain is varied by bias control than when varied by change of anode potential.

I have managed to modify the constants of the transformers in the range of automatic tuning so as to eliminate this instability without introducing any additional structure. I find that the instability referred to will cause oscillation in the amplifier when the volume control is varied to reduce the amplification to an intermediate value. The instability occurs at an intermediate rather than at lowest amplification for the reason that at very low or zero or negative gains the amplifier becomes inherently stable because of the absence of that amplification which is obviously essential to all regenerative phenomena. The oscillation may occur of itself when the instability is great, but when it is of slight extent the oscillation will only occur when a strong radio signal is impressed on the amplifier, causing slight additional changes in the bias and anode voltage beyond that provided by the voltage supply sources. 95

I have discovered that this instability is due to one output circuit attaining a higher natural frequency than a preceding input circuit, in combination with an input circuit virtually devoid of the normal damping exerted on it by the anode to cathode load of the preceding tube. More specifically, in the case of the stage including tube T^4 in the present amplifier the natural frequency of the output circuit including transformer 32 may become higher than that of the input circuit including transformer 28 at reduced 100 gain because while the apparent input capacitances of tubes T^4 and T^5 both diminish at reduced gain, that of tube T^4 diminishes more rapidly than that of tube T^5 . This effect carried sufficiently far will overcome the 105 lower initial natural frequency of transformer 32 relative to that of transformer 28, and to permit of a regenerative condition in tube T^4 . At the same time the increase in 110 impedance of tube T^5 at reduced gain reduces the damping or resistance load thereof across transformer 28, thereby more readily permitting regeneration from transformer 32, to 115 cause oscillation in transformer 28. 120

The cure for this condition of instability 130

I find to be two-fold. Firstly, in some stages to increase the inductance of the output transformer of a tube and associated pair of transformers creating the disturbance so that under all conditions of volume control its natural frequency of vibration never increases to a higher value than that of the input circuit associated with the same tube.

Secondly, in the third stage, including tube 10 T^s , where the input circuit has a lower natural frequency than the output circuit, the remedy is to slightly reduce the inductance of the output circuit and slightly increase the inductance of the input circuit so as to 15 separate by larger amounts than automatic tuning of the other stages requires the natural vibration or resonance frequency of the input and output circuits to the point where the regeneration is insufficient to cause oscillation in the input.

In both cases the variations from the mean values determined by the requirements for automatic tuning are small, so that the loss of efficiency to meet this condition is negligible.

Referring again to Fig. 2 of the drawing, it will be observed that a resistor 50 is connected in series with the anode supply lead, so that by varying the resistance thereof the 20 effective or operating anode potential applied to the anodes of the amplifier tubes may be varied, and this exemplifies one way to obtain volume control. Now, in accordance with the foregoing invention, the inductance 25 of transformer 28 is slightly reduced, thereby insuring that the input circuit of tube T^s will remain naturally resonant to a frequency higher than that of the output circuit, so that the stage including tube T^s will remain stable 30 throughout the range of volume control. Transformer 24 is slightly increased in inductance thereby causing, together with the decrease in the inductance of transformer 28, an augmented difference in the natural frequencies of the input and output circuits of 35 tube T^s , which leads to greater stability. The increase in inductance of transformer 24 causes the natural frequency thereof to be lowered, and further separated from the frequency of the transformer 21, and so prevents regenerative reaction through the tube 40 T^s . Transformer 36 might be increased in inductance to increase the frequency difference between transformers 32 and 36, but in 45 the case of a circuit like the present one, wherein transformer 36 works into a detector tube, or more broadly, an apparent small loss free capacitance, this precaution is unnecessary for the reason that the low natural resonance frequency of transformer 36 remains fixed and therefore transformer 36 can never 50 make transformer 32 oscillate.

These changes may be illustrated with reference to Fig. 3 in which the amplifier tubes 55 T^1 , T^2 , T^s , T^4 , and T^6 , and the detector tube

40 are schematically indicated as coupled by by transformers 21, 24, 28, 32, and 36, the heights of the rectangles representing the natural wave lengths thereof. Relative to the values determined in the absence of volume 70 control, the transformer dimensions are altered in accordance with the dotted line showings on Fig. 3, that is to say, the inductances of transformer 28 is decreased, the inductance of transformer 32 may be left unchanged by reason of a reduction in the inductance of transformer 28, while the inductance of transformer 24 is increased. It should be appreciated that these changes are all of second order magnitude, and are intended to correct what may be considered only as secondary defects, and that therefore the changes are all within the range of dimension which will successfully give the desired automatic tuning.

Referring again to Fig. 2, it will be observed that the anode potential for tubes T^1 and T^2 is supplied directly through lead 52 while the volume control means 50 is arranged to affect the anode potential of only 55 tubes T^s , T^4 , and T^6 connected through lead 54 to the variable resistance 50. This I find is important because if a variable potential is supplied to the anode of tube T^1 the apparent input capacitance thereof is varied, and this varies the tuning of the resonant circuit 12, and therefore alters the selectivity of the selector.

If a variable potential is applied to the anode of tube T^2 , the apparent input capacitance thereof also is varied, and this varies the capacitance hanging on the output circuit of tube T^1 , and thereby also varies the reaction of the amplifier upon the selector. In other words, the input capacitance characteristic of the tube T^2 having been selected to perfect the reactionlessness of tube T^1 , variation of this input capacitance by volume control injures its corrective effect upon the tube T^1 .

I therefore prefer to apply volume control only to tubes T^s , T^4 , and T^6 , and not to the transition or link stages T^1 and T^2 . However, it is possible to carry the foregoing precautions for stabilizing the amplifier further, and then to apply volume control to all of the tubes, with a slight sacrifice in selectivity.

Considering a few further details of the circuit in Fig. 2, it will be noted from the 120 wiring diagram that inductance 16 and transformers 21, 28, 32, and 36 consist of sections connected in series and wound in opposite directions. These sections are sufficiently spaced so that the desired total inductance is obtained, but at the same time are made astatic with respect to external magnetic fields, this arrangement being disclosed and described more in detail and claimed in my copending application, Ser. No. 402,379, 125 130

filed October 25, 1929. Transformer 24 need not be made astatic, if desired, for the reason that it is resonant to a frequency considerably lower than the working frequency range. Furthermore, if all of the other transformers are made astatic, transformer 24 is decoupled therefrom even though not made astatic. This fact is taken advantage of because transformer 24, if made astatic, would require a considerable number of sections, say 4 or 6 sections, for reasons next explained in connection with transformer 36, and such a multi-section construction would add to the manufacturing expense of the amplifier.

Transformer 36 is wound in four sections, whereas the other transformers are wound merely in two sections. This is done to fulfill an additional requirement other than astaticism, namely, that the transformer sections should not be naturally resonant to frequencies lying inside of the working frequency range, because this would tend to cause peaks or inflection points in the amplification and reaction characteristics which are undesired in the present amplifier. In accordance with the disclosure in my copending application, Ser. No. 402,379, filed October 25, 1929, previously referred to, this difficulty is overcome by subdividing each transformer into a number of sections such that the natural resonance frequency of a section lies outside of the working frequency range. In the case of transformers 21, 28, and 32, each section fulfills this requirement even though only two sections are employed. In the case of transformer 36, which has a relatively large inductance, it is necessary to obtain more than two sections if the natural resonance frequency of each section is to be removed from the working frequency band. It is convenient to use four equal sections because by winding alternate equal sections in opposite directions astaticism may be obtained and, in fact, the astaticism of a four section transformer such as the transformer 36, is more perfect than that of a two section transformer. This feature is not claimed herein, being claimed in the copending application Ser. No. 402,379, previously referred to.

It will further be noted that an inductance 38 is connected in series with the secondary of transformer 36 and the control electrode of the detector tube 40. This inductance is selected of such magnitude as will series resonate with the apparent tube input capacitance of the detector tube at a frequency slightly higher than the highest frequency of the working frequency band, thereby tending to boost the amplification of the higher frequencies. This is of advantage whenever the energy output is supplied to a tube having a capacitive input reactance, as is the case with a detector tube (the output circuit of which is shunted for radio frequency energy) because with a capacitive input circuit

the amplification tends to fall off at higher frequencies. The free grid inductance 38 is also preferably wound astatically, as is indicated on the wiring diagram. It is not claimed in the present application, being disclosed in greater detail and claimed in a copending application of Lester L. Jones and Jacob Yolles, Ser. No. 402,378, filed October 25, 1929.

The following is a suitable set of quantitative design values and dimensions for the amplifier illustrated in Fig. 2. Resistance 18 may have a value of 2800 ohms. Capacitance 20 may be 24 micro-microfarads. Inductance 16 consists of two coils arranged astatically, each coil consisting of 83 turns random wound in a pair of slots on a spool such as is illustrated and dimensioned in Fig. 4, the outside diameter of the winding being about 9/16 of an inch, and the total inductance of coil 16 being 0.22 milli-h. Transformer 21 is a bifilar transformer preferably formed by twisting primary and secondary wires together with a very long pitch and random winding the twisted wire in opposite directions in a pair of slots in order to obtain astaticism. The transformer consists of 210 turns in each slot of a pair of slots on a spool arranged and dimensioned as is indicated in Fig. 5 of the drawing, the outside diameter of the winding being about 3/4 of an inch, and the transformer having an inductance of 1.16 milli-h. Transformer 24 is a bifilar transformer consisting of 600 turns random wound in a single slot on a spool such as is illustrated in Fig. 6 of the drawing, the outside diameter of the winding being about one inch, and the transformer having an inductance of 4.45 milli-h. Transformer 28 is a bifilar transformer consisting of 150 turns wound in each of a pair of slots on a spool such as is illustrated in Fig. 5 of the drawing, the outside diameter of the winding being about 5/8 of an inch, and the transformer having an inductance of 0.64 milli-h. Transformer 32, like transformer 21, is a bifilar transformer consisting of 210 turns wound in each of a pair of slots on a spool such as is illustrated in Fig. 5 of the drawing, the winding having an outside diameter of 3/4 of an inch, and the transformer having an inductance of 1.16 milli-h. Transformer 36 is a bifilar transformer consisting of 250 turns in each slot of 4 alternately oppositely wound slots on a spool such as is illustrated in Fig. 7 of the drawing, the outside diameter of the windings being 7/8 of an inch, and the inductance of the transformer being 3.15 milli-h. Inductance 38 consists of 175 turns per slot in a pair of slots on a spool such as is illustrated in Fig. 4 of the drawing, the windings having an outside diameter of 11/16 of an inch, and the coil having an inductance of 1.01 milli-h. The foregoing dimensions assume the use of alternating cur-

rent heater type of tubes commercially denoted type 227, having a grid to plate capacitance of say 3 micro-microfarads, an amplification constant of say 13, and a tube impedance of say 1300 ohms. The spools are made of insulating material, which may be molded insulation, or impregnated wood.

The design constants previously given for the amplifier of Fig. 2 represent a considerable margin of safety on the side of stability, this design resulting in a stable amplifier regardless of whether the volume control is by variation of anode potential or by variation of grid bias, and regardless of whether the volume control is applied to the last three tubes or to all five of the tubes.

Attention is next directed to Fig. 8 of the drawing. This figure is substantially identical with that shown in Fig. 2 except that stage T^1 is coupled to stage T^2 by means of a condenser 119 in series with a coil 121, instead of by means of a bifilar transformer. The relative merits of the two coupling systems are discussed in my co-pending application, Ser. No. 397,632, previously referred to. Fig. 8 also differs in that the volume control resistor 150 is arranged to vary the anode potential applied to all of the tubes instead of merely the potential applied to the last three tubes. In a very high grade receiver in which excellent selectivity is of great importance I believe it preferable not to employ volume control in the transition stages T^1 and T^2 . In this case the volume control may best be supplemented by the variable inductive coupling means for volume control shown in Fig. 1 whereby the attenuation in the selector is made variable. This is to prevent the amplification of very strong local signals in T^1 and T^2 which would produce distortion in T^3 when the B or C potentials are greatly reduced. Fig. 2 with the selector coupling variation shown in Fig. 1 therefore would represent my invention in preferred form, but I have illustrated volume control applied to all five tubes in Fig. 8 because it is possible to produce a stable amplifier even when this is done.

When the amplifier is arranged for volume control by variation of anode potential in the manner illustrated in the drawing the following design constants may be employed. Resistance 118 may be 2800 ohms. Capacitance 120 may be 20 micro-microfarads. Inductance 116 consists of 85 turns in each of a pair of oppositely wound slots having a total inductance of 0.23 milli-h. Capacitance 119 is 240 micro-microfarads. Inductance 121 consists of 160 turns in each of a pair of oppositely wound slots and has an inductance of 0.8 milli-h. Transformer 124 is a bifilar wound transformer consisting of 550 turns wound in a single slot and having an inductance of 4.3 milli-h. Transformer 128 is a bifilar transformer consisting of 175

turns in each of a pair of oppositely wound slots and having an inductance of 0.81 milli-h. Transformer 132 is a bifilar transformer consisting of 210 turns in each of a pair of oppositely wound slots and has an inductance of 1.2 milli-h. Transformer 136 is a bifilar transformer consisting of 250 turns in each of 4 alternately oppositely wound slots and has an inductance of 3.1 milli-h. The use of alternating current tubes of the 227 type is assumed. This amplifier is stable for anode potential variation on 3 or 5 tubes.

If it is desired to use grid bias volume control instead of anode potential variation slight further changes in the direction of stability are necessary, transformer 124 being raised in inductance from 4.3 to 5.15 milli-h., and transformer 128 being decreased in inductance from 0.81 to 0.63 milli-h.

It will be apparent from the foregoing description that I have provided a cascade vacuum tube amplifier having fixed circuit constants, and which is untuned in that sense, but which nevertheless is automatically tuned to frequencies lying in a broad working frequency range. A plurality of tubes are automatically tuned, and the circuit constants are so adjusted that successive output circuits automatically tune preceding input circuits, even though the successive stages are coupled directly together in cascade. It will further be appreciated that the various difficulties met with when it is attempted to apply volume control to this amplifier circuit have also been solved, and that in consequence a stable and efficient automatically tuned amplifier is made available, the gain in which may be varied over a very wide range suitable for volume control of radio receiving circuits.

While I have shown and described my invention in the preferred forms, changes and modifications may be made in the structures disclosed without departing from the spirit of the invention, defined in the following claims.

I claim:

1. In automatic tuning with a plurality of amplifier stages having fixed constants, the method of making possible automatic tuning while coupling successive stages directly in cascade which includes dividing the working frequency range into a plurality of portions, and adjusting the circuit constants of each of the stages for automatic tuning in different portions of the working frequency range.
2. In automatic tuning with a plurality of amplifier stages having fixed constants, the method of making possible automatic tuning while coupling successive stages directly in cascade which includes dividing the working frequency range into a plurality of portions, adjusting the circuit constants of each of the stages for automatic tuning in different portions of the working frequency range,

and cascading the automatically tuned stages in the order of decreasing frequency portions, whereby the input circuit of a succeeding stage may operate as the output circuit for automatically tuning a preceding stage.

3. In the adjustment of a cascade automatically tuned amplifier comprising electron emission tubes, coupling circuits arranged to automatically tune preceding coupling circuits, and volume control means, the method of preventing instability over the range of volume control which includes so proportioning the input and output circuits of each tube, within the range giving the desired automatic tuning, that the natural resonance frequency of the input circuit remains higher than the natural resonance frequency of the output circuit over the range of volume control.

20 4. In the adjustment of a vacuum tube amplifier having fixed circuit constants and volume control means, the method of preventing instability over the range of volume control in a stage of amplification made regenerative by reason of the output circuit being naturally resonant to a frequency higher than the input circuit which includes making the input and output circuits sufficiently widely different in frequency to prevent instability.

30 5. In the operation of a receiver comprising a sharply tuned selector, a plurality of amplifier stages, a tube arranged as a transition stage between the amplifier stages and the selector, and volume control means to vary the gain in the amplifier, the method of preventing changes in the operational characteristics of the selector over the range of volume control which includes varying the gain in the amplifier stages but not varying the gain in the transition stage of the amplifier.

45 6. In the operation of a receiver comprising a sharply tuned selector, a plurality of electron emission tube stages arranged for automatic tuning, a plurality of tubes arranged as transition stages between the automatically tuned stages and the selector, and volume control means to vary the operating potential applied to the tubes in order to vary the gain therein, the method of preventing changes in the operational characteristics of the selector over the range of volume control which includes varying the potential applied to the automatically tuned stages of the amplifier but not varying the potential applied to the transition stages of the amplifier.

50 7. A cascade automatically tuned amplifier comprising a plurality of electron emission tubes, fixed circuits coupling the tubes directly in cascade, each coupling circuit being naturally resonant to a frequency lower than that of the preceding coupling circuit in order to obtain a decreasing capacitance characteristic with increasing frequency of

proper magnitude for automatically tuning the stages.

8. A cascade automatically tuned amplifier comprising a plurality of electron emission tubes, transformer means coupling the tubes directly in cascade, the transformer of each of the stages being naturally resonant to a frequency lower than that of the preceding stages in order to obtain a decreasing capacitance characteristic with increasing frequency of proper magnitude for automatically tuning each of the stages.

70 9. A cascade automatically tuned amplifier for use over a relatively broad working frequency range comprising a plurality of electron emission tubes, transformer means coupling the tubes directly in cascade, the output transformer of each of the stages being naturally resonant to a frequency lower than that of the input transformer of each of the stages in order to obtain a decreasing capacitance characteristic with increasing frequency for automatically tuning each of the stages, and the constants of each of the stages being adjusted to be automatically tunable over different portions of the working frequency range.

75 10. A cascade automatically tuned amplifier for use over a relatively broad working frequency range comprising a plurality of electron emission tubes, transformer means coupling the tubes directly in cascade, the output transformer of each of the stages being naturally resonant to a frequency lower than that of the input transformer of each of the stages in order to obtain a decreasing capacitance characteristic with increasing frequency for automatically tuning each of the stages, the constants of each of the stages being adjusted to be automatically tunable 80 over different portions of the working frequency range, and the stages being cascaded in the order of decreasing frequency.

85 11. A radio frequency amplifier having fixed circuit constants comprising a first electron emission tube and associated circuits the constants of which are selected to be substantially reactionless, a second electron emission tube and associated circuits the constants of which are selected to correct for residual reaction in the first tube, and an additional group of stages each comprising a tube and associated circuits the constants of which are selected to be automatically tunable over different portions of a relatively broad working frequency range, said stages being arranged in cascade in the order of decreasing frequency.

90 12. A radio frequency amplifier having fixed circuit constants comprising a first electron emission tube and associated circuits the constants of which are selected to be substantially reactionless, a second electron emission tube and associated circuits the constants of which are selected to be automatic- 100 110 115 120 125 130

- cally tunable and to correct for residual reaction in the first tube, and an additional group of stages each comprising a tube and associated circuits the constants of which are selected to be automatically tunable over different portions of a relatively broad working frequency range, said stages being arranged in the order of decreasing frequency, and being coupled directly in cascade.
- 10 13. A radio frequency amplifier having fixed circuit constants comprising a first electron emission tube, an output circuit therefor the constants of which are selected to make the tube substantially reactionless, a second electron emission tube, input and output circuits therefor the constants of which are so related as to cause a rising apparent input capacitance characteristic with decreasing frequency in order to obtain automatic tuning and to correct for residual reaction in the first tube, a third electron emission tube, and an additional group of stages each comprising a tube and associated circuits the constants of which are selected to be automatically tunable over different portions of a relatively broad working frequency range, said stages being arranged in the order of decreasing frequency, and being coupled directly in cascade.
- 20 14. A radio frequency amplifier having fixed circuit constants comprising a first electron emission tube arranged to be substantially reactionless, a second electron emission tube, input and output transformers therefor respectively resonant to high and low frequencies in order to obtain automatic tuning and to correct for residual reaction in the first tube, an additional group of tubes, and transformers therefor each naturally resonant to a frequency lower than that of a preceding transformer in order to obtain automatic tuning over successive portions of a relatively broad working frequency range.
- 30 15. A radio frequency amplifier having fixed circuit constants designed for operation over a relatively broad working frequency range, said amplifier comprising a first electron emission tube and associated circuits the constants of which are selected to be substantially reactionless, a second electron emission tube and associated circuits the constants of which are adjusted for automatic tuning and to correct for residual reaction in the first tube, a third electron emission tube, a fourth electron emission tube having input and output circuits the constants of which are so related as to obtain automatic tuning over the upper portion of the working frequency range, and a fifth electron emission tube having input and output circuits the constants of which are so related as to obtain automatic tuning over the lower portion of the working frequency range, all of said tubes being coupled directly in cascade.
- 40 16. A radio frequency amplifier having fixed circuit constants designed for operation over a relatively broad working frequency range, said amplifier comprising a first electron emission tube, an output circuit therefor the constants of which are selected to make the tube substantially reactionless, a second electron emission tube, input and output circuits therefor the constants of which are so related as to cause a rising apparent input capacitance characteristic with decreasing frequency in order to correct for residual reaction in the first tube, a third electron emission tube, a fourth electron emission tube having input and output circuits the constants of which are so related as to obtain automatic tuning over the upper portion of the working frequency range, and a fifth electron emission tube having input and output circuits the constants of which are so related as to obtain automatic tuning over the lower portion of the working frequency range, all of said tubes being coupled directly in cascade.
- 50 17. An automatically tuned amplifier comprising an electron emission tube, associated input and output circuits, and volume control means, the constants of the input and output circuits of said tube being so proportioned that the natural frequency of the input circuit remains always higher than the natural frequency of the output circuit over the whole range of volume control.
- 60 18. A cascade automatically tuned amplifier comprising electron emission tubes, coupling circuits having fixed constants so chosen as to automatically tune preceding coupling circuits, and volume control means, the constants of the input and output circuits of a plurality of said tubes being so proportioned, within the range providing the desired automatic tuning, that the natural frequency of the input circuit remains always higher than the natural frequency of the output circuit over the whole range of volume control.
- 70 19. A cascade automatically tuned amplifier comprising electron emission tubes, coupling circuits having fixed constants so chosen as to automatically tune preceding coupling circuits, and volume control means to vary the operating potential applied to the tubes in order to vary the gain therein, the constants of the input and output circuits of a plurality of said tubes being so proportioned, within the range providing the desired automatic tuning, that the natural frequency of the input circuit remains always higher than the natural frequency of the output circuit over the whole range of volume control, in order to prevent instability of the amplifier at any point in the range of volume control.
- 80 20. A cascade untuned amplifier comprising a plurality of electron emission tube stages, coupling means having constants re-

- lated to automatically tune preceding coupling means, volume control means for varying the total gain through a wide range, the constants of adjacent nearly resonant coupling means being so proportioned that the natural frequency of an input circuit is higher than that of the output circuit over the whole range of volume control in order to prevent instability throughout this range. 5
21. An automatically tuned amplifier comprising electron emission tubes and coupling circuits naturally resonant to different frequencies in or near the working frequency range, the output circuit of one of said tubes being naturally resonant to a frequency higher than the input circuit of said tube and therefore regenerative, the natural frequencies of the input and output circuits of said tube being sufficiently widely separated, in or near the working frequency 10 range, to prevent instability. 70
22. An automatically tuned amplifier comprising electron emission tubes, coupling circuits naturally resonant to different frequencies in or near the working frequency range, and volume control means, the output circuit of one of said tubes being naturally resonant to a frequency higher than the input circuit of said tube, the natural frequencies of the input and output circuits of said tube being sufficiently widely separated to prevent instability over the range of volume control. 20
23. An automatically tuned amplifier comprising electron emission tubes, coupling circuits naturally resonant to different frequencies, and volume control means for varying the operating potential applied to a plurality of said tubes, said plurality of tubes having output circuits naturally resonant to frequencies lower than the input circuits, one of said tubes having an output circuit naturally resonant to a frequency higher than the input circuit of said tube, the natural frequencies of the input and output circuits of said tube being sufficiently widely separated to prevent instability over the range of volume control. 30
24. An untuned amplifier comprising a preceding circuit, a group of automatically tuned stages, a stage between said preceding circuit and said group of stages, the output circuit of said stage having a natural frequency higher than that of the input circuit, and volume control means for varying the total gain over a wide range, the natural frequency of the circuits of said stage being widely separated in order to prevent instability over the range of volume control. 40
25. An untuned amplifier comprising a preceding circuit, a group of automatically tuned stages, a stage between said preceding circuit and said group of stages, the output circuit of said stage having a natural frequency higher than that of the input circuit, and volume control means for varying the total gain over a wide range, the natural frequency of the circuits of said stage being widely separated in order to prevent instability over the range of volume control. 50
26. The combination with a radio circuit comprising a sharply tuned selector, amplifier stages, and a transition stage between the selector and the amplifier stages, of means to control the gain in the amplifier stages, but not in the transition stage. 75
27. The combination with a radio circuit comprising a sharply tuned selector, automatically tuned amplifier stages, and a transition amplifier stage between the selector and the automatically tuned stages for preventing selectivity disturbing reactions from the automatically tuned stages to the selector, of means to control the gain in the amplifier comprising means to vary the operating potential applied to the automatically tuned stages, but not that applied to the transition stage. 80
28. The combination with a radio circuit comprising a sharply tuned selector, automatically tuned amplifier stages, and transition amplifier stages between the selector and the automatically tuned stages, of means to control the gain in the amplifier comprising means to vary the operating potential applied to the automatically tuned stages, but not the operating potential applied to the transition stages, in order to prevent variations in the operational characteristics of the selector. 90
29. The combination of a selector system comprising a plurality of cascaded circuits tunable over a broad band and having overall sensitivity decreasing with wave length over the tuning range, a non-tunable amplifier connected to the selector system, and means in said non-tunable amplifier for amplifying the said band with a gain characteristic increasing with wave length over the tuning range so as to compensate for the decreasing sensitivity of the selector system. 100
30. The combination of a selector system comprising a plurality of capacitively tuned cascaded circuits tunable over a broad band and having an overall sensitivity decreasing with wave length over the tuning range, a non-tunable tube amplifier system connected to the selector system, and means in said amplifier for amplifying this band with a gain characteristic increasing with wave length over the tuning range, whereby the combination possesses a high and reasonably constant degree of amplification. 110
31. The combination of a selector system 120

tunable over a broad band and having sensitivity decreasing with wave length over the tuning range, a non-tunable amplifier connected to the selector system for amplifying this band with a gain characteristic increasing with wave length over the tuning range, and means for eliminating the selectivity disturbing reactions of said amplifier on said selector system.

10 Signed at New York in the county of New York and State of New York this 2nd day of October, A. D. 1929.
